UNITED STATES PATENT OFFICE.

ANTHONY SCHROEDER, OF CLEVELAND, OHIO, ASSIGNOR OF ONE-HALF TO JAMES MERLE FINNEY, OF CLEVELAND, OHIO.

PUMP.

Application filed July 29, 1922. Serial No. 578,314.

To all whom it may concern:

Be it known that I, ANTHONY SCHROEDER, a citizen of the United States, residing at Cleveland, in the county of Cuyahoga and State of Ohio, have invented certain new and useful Improvements in and Relating to Pumps, of which the following is a specification.

This invention relates to a pump preferably of the reciprocating piston type.

One object of the invention is to provide an improved pump of relatively simple construction, whereby it may be economically made and readily operated.

Another object of the invention is to provide a reciprocating piston type of pump in which the inlet port and outlet port for the material are controlled by a member interposed between the pump cylinder and piston, whereby the latter may actuate such member to open one port and close the other at the proper time as the piston moves in either direction.

A further object of the invention is to provide an improved construction of reciprocating pump in which the cylinder comprises a pair of inner and outer members, the inner member being movable relative to the outer member, whereby the engagement of the piston therewith may be utilized to control the inlet and outlet ports for the material.

Other objects of the invention will be apparent to those skilled in the art to which my invention relates from the following description taken in connection with the accompanying drawings:

Referring to the drawings, Fig. 1 is a sectional view of the pump embodying my invention showing the piston at or near the end of its suction stroke.

Fig. 2 is a view similar to Fig. 1, but showing the piston at the end of its force stroke.

Fig. 3 is a section on the line 3—3 of Fig. 2.

Fig. 4 is a section on the line 4—4 of Fig. 3.

Fig. 5 is a section on the line 5—5 of Fig. 3.

Fig. 6 is a sectional view of a pump embodying my invention, showing its adaptation to a container; portions of the pump elements being slightly modified for such adaptation.

Figs. 7, 8, 9 and 10 are sections on the line 7—7, 8—8, 9—9 and 10—10, respectively, of Fig. 6.

In the drawings, 1 indicates a cylinder formed from any suitable material. The opposite ends of the cylinder 1 are threaded as shown at 2, 2^a, whereby a cap 3 may be connected to one end of the cylinder and a casing member 4 attached at its other end. The cap 3 is formed with a central opening 3^a for a piston rod 5. The piston rod 5 may be operated by any suitable means, that shown comprising a handle 6 connected to the free end of the rod in a well known manner. The opening 3^a is provided with screw threads to receive and support a sleeve 7. The sleeve 7 may be rotated in the opening 3^a to adjust it endwise therein for a purpose to be latter set forth. The outer end of the sleeve 7 is fashioned to receive a suitable tool whereby it may be readily turned. Eight indicates the piston which is fixed to the rod 5 in the manner to be latter described. The casing member 4 comprises a body portion 8' in axial alignment with the cylinder 1 and receiving and discharging nipples 9, 10, respectively, whereby a supply conduit or pipe may be connected to the former and a discharge pipe connected to the latter. At 11, the casing member is shaped to form a seat for the adjacent end of the cylinder 1. Twelve indicates a port formed in the wall of the body portion 8' for the intake of material from the nipple 9 thereinto, such port being preferably elongated circumferentially of the body portion to admit the material freely. Between the inlet port 12 and the other end of the pump cylinder 1, the body portion 8' is formed with a discharge port 13 communicating with the discharge nipple 10. By preference, the body portion 8' is shaped or fashioned to provide around its interior wall an annular chamber 14, which merges with or is connected at one side with the discharge port 13.

15 indicates a member movably mounted within the cylinder 1 and controlled by the piston 8 to open one of the ports 12 and 13 and close the other, when the piston 8 moves in either direction. The member 15 preferably comprises a cylinder loosely fitting the cylinder 1 so that it may move endwise thereof in an axial direction. The length of the cylinder 15 is substantially 110

equal to the distance from that wall 16 of the casing member 4 which closes the adjacent end of the pump to the cap 3 less the distance the ports 12 and 13 are spaced from each other for reasons which will later appear. By this arrangement, the wall 16 and cap 3 may act as stops to limit the movement of the cylinder in either direction. 17 indicates an opening formed in the wall of the cylinder 15 and so arranged that it will register with the port 13 when the cylinder is positioned with that end thereof that is adjacent to the port 12 against the stop 16. While only one opening 17 is shown, it is obvious that as many openings as desired may be formed in the cylinder 15 for registry with the port 13 or the chamber 14 to permit the discharge of the material. As shown in the drawings, the piston 8 reciprocates in the cylinder 15 and through its frictional engagement with the cylinder 15 moves it endwise or axially, whereby the cylinder may control the ports 12 and 13 to prevent discharge of the material through the inlet port during the force stroke of the piston or sucking in of the material through the discharge port 13 during the suction stroke of the piston; for example, starting with the piston 8 in the position shown in Fig. 2, where it is at the end of its force stroke and ready to move in the opposite direction: as the piston 8 moves upwardly, it first moves the cylinder 15 axially into the position shown in Fig. 1, this operation moving (1) the opening 17 out of registry with the port 13 and chamber 14 and (2) the open end of the cylinder 15 beyond the inlet port 12. As the piston continues to move upwardly, it sucks in a charge of material through the nipple 9 and port 12, filling the cylinder 15. The piston may be operated a full stroke or less than a full stroke, as desired. In its reverse movement, the piston 8 first moves the cylinder 15 endwise or axially in the opposite direction—that is, downwardly as shown in the drawings—this operation serving to move the cylinder 15 to the position shown in Fig. 2, thereby closing the port 12 and moving the opening 17 into registry with the port 13 or chamber 14, so that as the piston 7 continues to move downwardly the material will be forced out through the opening 17, chamber 14, port 13 and nipple 10. In order to insure proper and uniform coaction between the cylinder 15 and walls of the ports 12 and 13, as well as to avoid leaks of the material, the body portion 8' of the casing member is preferably of a size to fit the cylinder 15 relatively closely. If desired, the body portion 8' may be formed with oil containing grooves 18.

The piston 8 preferably comprises a disk 19 having screw threaded connection with the piston rod 5, one or more flexible members 20 having flanged portions 20^a which

engage the cylinder 15 and a device 21 which has screw threaded connection with the piston rod 5 and may be screwed up thereon to clamp the flexible members against the disk 19. The securing device 21 is preferably provided with a projecting member 22 arranged to engage the end wall or stop 16 of the casing member 4 to stop the movement of the piston 8 at a point adjacent to the port 13. 75

23 indicates a spring which is preferably provided to act against the flanged portion 20^a of one of the flexible members 20 of the piston 8 to increase the friction between it and the cylinder 15. The spring 23 preferably extends circumferentially around the inner side of the flanged portion 20^a and serves to press the flanged portion outwardly. In the construction illustrated, the spring 23 comprises a coiled spring, a groove 23^a being provided in the circumferential edge of the disk 19 to receive it. In Fig. 6, I have illustrated my pump construction as adapted for use in a container A. In this construction the casing member 4' is shaped to provide feet 24 which may be secured to the bottom of the container by screws 25. As the pump is immersed in the material placed in the container, the walls of the casing member may be provided with a plurality of inlet openings or ports 26 and the discharge nipple 10' is extended upwardly for connection with a pipe 26^a which extends to a point near the open end of the container, where it may extend laterally through the side wall 100 of the container. The container A may be formed in any suitable manner. When provided with a top, indicated at a, an opening 27 is formed therein to permit the piston rod that is connected to the handle 6' to extend 105 through the top for operation.

It will be noted that the elements of my pump construction are relatively few in number and easily manufactured and assembled. While the cylinder 15 is arranged to move axially, it may be rotated without affecting its operation, or the control of the ports 12 and 13, since the chamber 14 extends circumferentially of the casing member and is adapted to receive material from the opening 17 in any position angularly of the cylinder 1 in which the cylinder 15 may be assembled or be moved to by reason of the twisting of the handle 6 accidentally or otherwise. The construction 110 of pump is adyantageous in that it eliminates the necessity of providing valves in the pump cylinder or the end walls therefor or in the piston. It will also be noted that in my construction of pump there is but one movable element in addition to the piston. 115

The pump is adapted for pumping various kinds of material. In practice I have successfully used it for the pumping of greases and lubricants containing relatively 120

thick and heavy ingredients. I have found by experience that my pump construction is advantageously adapted for pumping measured quantities of materials. In the manufacture of the pump, I provide a cylinder 1 which is slightly larger in capacity than the quantity of material which it is desired to discharge at each force stroke of the piston; and also means which control the distance of travel of the piston in its suction stroke so that it will suck in a predetermined quantity of material. The control means for limiting the travel of the piston consists of the sleeve 7, already described, the inner end of which is disposed in the path of movement of the piston so as to be engaged thereby as the piston moves toward the cap 3. By rotating the sleeve 7 to adjust its inner end, the piston 8 may be stopped at any desired point and thus be made to suck in a predetermined quantity of the material. As the piston is moved in the force stroke a predetermined distance, it will be seen that in each complete operation of the piston a measured quantity of material will be sucked in and discharged from the cylinder.

To those skilled in the art of making apparatus of the class described, many alterations in construction and widely differing embodiments and applications of my invention will suggest themselves, without departing from the spirit and scope thereof. My disclosures and the description herein are purely illustrative and are not intended to be in any sense limiting.

What I claim is:

1. In apparatus adapted for delivering measured quantities of greases and like semi-fluid substances, the combination of a pump cylinder having an inlet port and an outlet port near one end, the inlet port being disposed between the outlet port and the end of the pump cylinder that is adjacent to the said ports, a freely movable inner cylinder within the pump cylinder that is open at the end which is adjacent to the said ports and is formed with a port arranged to register with the outlet port in the pump cylinder when the inner cylinder is moved in one direction and closes the inlet port, and is out of register with the outlet port when the cylinder is moved in the other direction and the inlet port is uncovered, and a piston movable within the said inner cylinder and operating to move it when the piston is operated.

2. In apparatus of the class described, the combination of an outer cylinder, an inner cylinder arranged within and movable endwise of said outer cylinder, and a piston engaging said inner cylinder and serving to move it endwise of said outer cylinder when moving in either direction, said outer cylinder being formed near one end with

an inlet and an outlet spaced apart in the direction of the length of the cylinder, and said inner cylinder being open at that end adjacent the inlet in the outer cylinder, and arranged to alternately open and close the inlet of the outer cylinder as it is moved endwise, and the inner cylinder being formed with an outlet disposed to register with the outlet in said outer cylinder when the piston is moved in one direction.

3. In apparatus of the class described, the combination of a stationary pump cylinder to one end of which is secured a casing in which is formed an inlet located near the end of the casing and an outlet located nearer the cylinder than the inlet, an inner cylinder movable within said pump cylinder, said inner cylinder being open at that end adjacent to the casing closing the end of the outer cylinder and extending into and fitting within the said casing, the inner cylinder being formed with an outlet arranged to register with the outlet in said casing when said inner cylinder is moved in one direction relative thereto, and a piston frictionally engaging said inner cylinder to move it when the piston is operated, whereby the inlet and outlet in the casing at the end of the pump cylinder are controlled.

4. In apparatus of the class described, the combination of a pump cylinder having an inlet and an outlet near one end, said inlet being disposed between one end of said pump cylinder and the outlet formed therein, an inner cylinder movable within said pump cylinder, said inner cylinder being open at that end adjacent to the inlet in said pump cylinder and formed with an outlet arranged to register with the outlet in said pump cylinder when said inner cylinder is moved in one direction relative thereto, a piston frictionally engaging said inner cylinder to move it when the piston is operated, whereby the inlet and outlet of said pump cylinder are controlled, and means for adjusting the stroke of the piston.

5. In apparatus of the class described, the combination of inner and outer relatively movable cylinders, a piston arranged therewithin and engaging the inner cylinder to move it relative to said outer cylinder, said outer cylinder being formed with an inlet and an outlet and said inner cylinder being formed with an outlet adapted to register with the outlet in said outer cylinder when the piston is moved in one direction and disposed out of registry therewith when the piston is moved in the opposite direction, means for limiting the movement of the inner cylinder in either direction, and adjustable means for limiting the movement of the piston in either direction.

6. In apparatus of the class described, the combination of inner and outer relatively movable cylinders, and a piston arranged

therewithin and engaging the inner cylinder to move it relative to said outer cylinder, said outer cylinder having at one end a casing formed with an inlet and an outlet and 5 an annular chamber connected to said outlet, and one end of said inner cylinder extending into the said casing and being formed with an outlet adapted to register with said annular chamber when the piston is moved 10 in one direction to a predetermined position and disposed out of registry therewith when the piston is moved in the opposite direction and the end of the inner cylinder being arranged to alternately cover and uncover 15 the inlet as the inner cylinder is moved by the piston.

7. In a pump construction, the combination of a cylinder having heads at its opposite ends, said cylinder being formed with 20 an inlet opening adjacent one head and an outlet opening intermediate its ends, a cylindrical valve member arranged within and being of less length than said cylinder and movable endwise therein to permit engagement of one end of said member with the head adjacent to the said openings, whereby it co-acts therewith to close said inlet opening, and disengagement from said head to uncover said inlet opening, said valve member being formed with a single opening adapted to register 25 with said outlet opening when said member is in the first mentioned position, a piston frictionally engaging said valve member to actuate it 30 and movable relative thereto to effect pumping action into and out of said cylinder.

8. In a pump construction, the combination of a cylinder having heads at its opposite ends, said cylinder being formed with an inlet opening adjacent one head and an outlet opening intermediate its ends, a cylindrical valve member arranged within and being of less length than said cylinder and movable endwise therein to permit engagement of one end of said member with the 40 adjacent head, whereby it co-acts therewith to close said inlet opening, and disengagement from said head to uncover said inlet opening, said valve member being formed with a single opening adapted to register 45 with said outlet opening when said member is in the first mentioned position, a piston frictionally engaging said valve member to actuate it 50 and movable relative thereto to effect pumping action into and out of said cylinder, the difference in length of said cylinder and member being substantially equal to the distance between said inlet and outlet openings, whereby the head adjacent the inlet opening serves to position the opening 55 in said member in registry with said outlet opening when the piston moves in one direction and adjustable means for limiting the movement of the piston in each direction.

In testimony whereof, I have hereunto 60 signed my name.

ANTHONY SCHROEDER.
